(No Model.)

H. P. OLMSTEAD.

BUSTLE.

No. 368,106.

Patented Aug. 9, 1887.

UNITED STATES PATENT OFFICE.

HOMER P. OLMSTEAD, OF NEW YORK, N. Y.

BUSTLE.

SPECIFICATION forming part of Letters Patent No. 368,106, dated August 9, 1887.

Application filed April 27, 1886. Serial No. 200,266. (No model.)

To all whom it may concern:

Be it known that I, HOMER P. OLMSTEAD, of New York, in the county of New York and State of New York, have invented a new and useful Improvement in Bustles, of which the following is a specification.

In the manufacture of bustles the steels or bones which are employed as stiffeners are ordinarily held in place by pockets upon the inner side of the bustle-body, and extend either horizontally, or both horizontally and diagonally, as in long bustles. These steel or bone pockets are commonly formed by stitching what is termed a "pocket-strip" to the inner side of the bustle-body, and this pocket-strip at its ends is usually turned inward and sewed down, so as to form at the end of the pocket a guard for the end of the steel or bone. In use, however, as there is but a single thickness of material at the end of the pocket-strip to shield the steel or bone; the fabric is soon worn out and the end of the steel or bone allowed to protrude.

The object of my invention is to provide a simple and effective means for more thoroughly protecting the ends of the pocket-strips to prevent the steels or bones from wearing through, such means being secured upon the inner side of the body of the bustle and being entirely concealed from view by the body, and to this end my invention consists in an end-protection strip, which extends transversely to the pocket-strips and is folded longitudinally before it is stitched to the body, so as to form inner and outer flaps or members to receive between them the ends of the pocket-strips and the steels or bones which the pocket-strips contain, the end-protection strips being secured to the body with both flaps or members upon the inner side of the body and entirely concealed from view by the body. This end-protection strip may be made of a single piece or strip of webbing folded longitudinally; but I prefer to form it by first doubling the strip of fabric and folding such strip longitudinally, so as to give in both the outer and inner flaps or members of the end-protection strip a double thickness of fabric overlying and underlying the end of the steel or bone, and which is additional to the thickness of fabric in the pocket-strip.

The invention also consists in other details of construction, all of which contemplate the use of an end-protection strip of the kind above referred to, and which are hereinafter described, and pointed out in the claims.

In the accompanying drawings, Figure 1 is an inside view of a short bustle embodying my invention, a portion of the outer flap or member of one of the end-protection strips being broken away to show more clearly the relation of these end-protection strips to the pocket-strips. Fig. 2 is a horizontal section of a portion of the bustle shown in Fig. 1, taken, for example, on the plane of the dotted line xx , Fig. 1, and upon a larger scale. Fig. 3 represents the inside of a portion of a long bustle, such as is usually provided with apron-fronts at the opposite sides of the body, and which also embodies my invention, a portion of the outer flap or member of the end-protection strip being also removed. Fig. 4 is a horizontal section on the plane of the dotted line yy , Fig. 3, also upon a larger scale. Fig. 5 represents a sectional view of a piece of doubled fabric before it is folded to form the end-protection strip, and Fig. 6 represents such fabric after it is folded to form the end-protection strip.

Similar letters of reference designate corresponding parts in all the figures.

I will first describe the bustle shown in Figs. 1 and 2. A designates the body, which may be made in any ordinary or suitable way and of suitable material, and B designates what is ordinarily termed the "center," whereby the bustle is given more or less projection, which may be varied by the tapes or ties b . The bustle is provided with steels or bones c , such as are ordinarily used, and which are arranged within pocket-strips d , extending transversely across the inner side of the body A and stitched thereto at opposite edges.

The essential elements of my invention are end-protection strips C, which are attached one at each end of the pocket-strips d , and which extend upward and downward or transversely to the said pocket-strips, the end-protection strips being entirely upon the inner side of the body and concealed by the body. These end-protection strips are formed of a piece of webbing or fabric folded so as to con-

stitute inner and outer flaps or members, *e e'*. The end-protection strips *C* are, however, preferably made of a double fabric, such as is shown in transverse section in Fig. 5, and which is 5 afterward folded longitudinally, to give it the form shown in Fig. 6, and this construction I deem preferable, because by this a double thickness of fabric is obtained in the outer flap or member, *e'*, outside the end portion of 10 the pocket-strip *d*, which is inserted between the two flaps or members *e e'*, as shown in the lower portion of Fig. 1, where the outer flap or member, *e'*, is broken away. The folded end-protection strip is first stitched to the body by 15 a line of stitching, *f'*, extending along close to the fold, and the inner edge of the inner flap or member, *e*, is then sewed to the body by a line of stitching, *f*, after which the pocket-strips *d* are sewed on above the inner flap or 20 member, *e*. After the pocket-strips *d* are secured in place the final sewing of the end-protection strip *C* is formed by lines of stitching *f''* at some distance from the folded edge, and being carried around the ends of the pocket-strips *d*, as shown at *f''*. When thus 25 constructed, the end portion of the pocket-strip *d* and the steel or bone *c* contained therein will be received or shielded within the folded strip of doubled fabric *C*, and the end of the steel or 30 bone will be protected by six thicknesses of fabric or web, three thicknesses on each side of the steel or bone—namely, on the inside, or the side most distant from the body, by the single thickness of the pocket-strip and by the 35 double thickness in the outer flap or member, *e'*, of the end-protection strip, and on the opposite side by the same double thickness in the inner flap, *e*, of the end-protection piece, and also the single thickness of the body of the 40 bustle. In this example of my invention the outer flap or member, *e'*, of the folded strip *C* is somewhat wider than the inner flap or member, *e*, and the portion of the outer flap or member, *e'*, which is inward of the line of stitching 45 *f''*, is left free, as shown in Fig. 2, and serves as a place of attachment for the straps of the adjustable center *B*.

In Figs. 3 and 4 I have represented a portion of what is usually known as a "long bustle," 50 *A* being the body, and *A'* a portion of the apron-front, which is united to the body by a seam, *h*. This bustle not only has the pocket-strips *d* arranged horizontally for the horizontal steels or bones *c*, but it also has diagonal 55 pocket-strips *d'*, containing diagonal steels or bones *c'*. In this example, also, the end portions of the pocket-strips *d*, and the steels or bones which they contain, are received between the inner and outer flaps or members, 60 *e e'*, of an end-protection strip, *C*, which extends transversely to the pocket-strips *d*. This end-protection strip may also be made of a single piece of webbing; but I prefer to make it of a piece of fabric doubled and then folded longitudinally, as shown in Figs. 5 and 6. The 65 folded end-protection strip *C* is first secured

to the body or to the apron at the front by a line of stitching, *f'*, through both the inner and outer flaps, *e e'*, and close to the folded edge, and the inner flap or member, *e*, is then 70 secured by a line of stitching, *f*, to the body, and the pocket-strips *d* are sewed on over the inner flap or member; and, finally, the securing of the end-protection strip *C* is completed by a line of stitching, *f''*, similar to that before 75 described with reference to Fig. 1, which passes through both the inner and outer flaps or members and around the ends of the pocket-strips *d*, as shown at *f''*. In this example of 80 my invention, however, the adjustable center *B* is not attached directly to the end-protection strips *C*, and the outer flap or member, *e'*, is therefore made narrower than the inner flap or member, *e*, and the line of stitching *f''*, which passes through the outer flap or member, *e'*, is 85 near the edge thereof.

It will be observed that in the bustle shown in Fig. 3 the end-protection strip *C* covers the seam *h*, whereby the apron-front is united to the body, and hence this need not be made a 90 felled seam, as is usual.

From the foregoing description it will be seen that according to my invention the end-protection strips *C* have both their flaps or members *e e'* secured upon the inner side of 95 the body, and hence the end-protection strip is entirely concealed by the body, and the body and apron-front are not impaired in appearance by the exposure on their outer surface of any portion of the end-protection strip.

I am aware of Letters Patent No. 188,092, granted March 6, 1877, to T. C. Barclay, and I do not claim as of my invention the construction therein shown. In that patent the body of the bustle has applied to it an edge-binding, one fold or flap of which is upon the inner side of the body and the other fold or flap of which is upon the outer side of the body.

What I claim as my invention, and desire to 110 secure by Letters Patent, is—

1. In a bustle, the combination, with a body and pocket-strips sewed to the body, of folded end-protection strips extending transversely to the pocket-strips and receiving between 115 their flaps or members the end portions of the pocket-strips and the steels or bones which said pocket-strips contain, the end-protection strips being secured with both flaps or members on the inner side of the body and being 120 concealed from view by the body, substantially as herein described.

2. In a bustle, the combination, with a body and pocket-strips *d*, sewed to the body, of end-protection strips *C*, extending transversely to 125 the pocket-strips and composed of a double fabric folded lengthwise to form the outer and inner flaps or folds, *e e'*, which receive between them the end portions of the pocket-strips and the steels or bones which they contain, the 130 end-protection strips being secured to the body with both flaps or folds on the inner side of

the body and being concealed from view by the body, substantially as and for the purpose herein described.

3. In a bustle, the combination, with a body and pocket-strips *d*, sewed to the body, and an apron-front extending beyond the body, of end-protection strips extending transversely to the pocket-strips and folded longitudinally to form inner and outer flaps or folds, *e e'*, which receive between them the end portions of the pocket-strips and the steels or bones which they contain, the end-protection strips being secured to the body with both the folds on the inner side thereof, at the junction of the body and apron-front, substantially as herein described.

4. In a bustle, the combination, with a body and pocket-strips *d*, sewed to the body, of end-protection strips extending transversely to the pocket-strips and folded longitudinally to form inner and outer folds or members, *e e'*, receiving between them the end portions of the pocket-strips and the steels or bones which they contain, the end-protection strips being secured to the body with both folds or mem-

bers on the inner side of and concealed by the body, and the adjustable center, the straps of which are connected directly with the flap *e'* of the end-protection strip, substantially as herein described.

5. In a bustle, the combination, with a body and pocket-strips *d*, sewed to the body, of the end-protection strips extending transversely to the pocket-strips and folded longitudinally to form inner and outer flaps or members *e e'*, which receive between them the end portions of the pocket-strips and the steels or bones which they contain, the end-protection strips being secured to the body with both flaps or members upon the inner side of the body, by lines of stitching through the inner flap or member, and by the lines of stitching *f' f''* through both flaps or members at the fold and around the ends of the pocket-strips, substantially as herein described.

HOMER P. OLMSTEAD.
